(57) **CLAIM**

The ornamental design for a hat with shadow image, as shown and described.

DESCRIPTION

FIG. 1 is a perspective of a first embodiment of a hat with shadow image according to the invention;

FIG. 2 is a top plan view of the hat with shadow image of FIG. 1;

FIG. 3 is a front elevational view of the hat with shadow image of FIG. 1;

FIG. 4 is a left side elevational view of the hat with shadow image of FIG. 1;

FIG. 5 is a right side elevational view of the hat with shadow image of FIG. 1;

FIG. 6 is a rear elevational view of the hat with shadow image of FIG. 1;

FIG. 7 is a left side elevational view of a second embodiment of a hat with shadow image according to the invention;

FIG. 8 is a right side elevational view of the second embodiment of the hat with shadow image of FIG. 7; and, FIG. 9 is a rear elevational perspective view of the second embodiment of the hat with shadow image of FIG. 7.

The broken line portions of the above drawings are for illustrative purposes only and do not form part of the design claimed herein.
